UNITED STATES PATENT OFFICE.

VICTOR W. KLIERSRATH AND FREDERICK A. HOYT, OF EAST ORANGE, NEW JERSEY,
ASSIGNORS TO THE SIMMS MAGNETO COMPANY, OF EAST ORANGE, NEW JERSEY,
A CORPORATION OF NEW JERSEY.

IGNITION APPARATUS FOR INTERNAL-COMBUSTION ENGINES.

1,398,491.

Specification of Letters Patent.

Patented Nov. 29, 1921.

Application filed July 15, 1921. Serial No. 484,876.

To all whom it may concern:

Be it known that we, VICTOR W. KLIERSRATH and FREDERICK A. HOYT, citizens of the United States, residing at East Orange, in the county of Essex and State of New Jersey, have invented certain new and useful Improvements in Ignition Apparatus for Internal-Combustion Engines; and we do hereby declare the following to be a full, clear, and exact description of the invention, such as will enable others skilled in the art to which it appertains to make and use the same.

Our invention consists in the novel features hereinafter described, reference being had to the accompanying drawings which illustrate one embodiment of the same, selected by us for purposes of illustration, and the said invention is fully disclosed in the following description and claims.

In the manufacture of two spark or double spark magnetos, for use with internal combustion engines, each engine cylinder is provided with two spark plugs which are connected with the secondary coil (or coils) and sparks are produced simultaneously at both spark plugs to insure the complete and rapid firing and combustion of the charges of explosive mixture. In the manufacture of magnetos of this type it frequently happens that one of the coils burns out or becomes short-circuited, thereby rendering the operation of the magneto ineffective and where, as is usually the case, these magnetos are employed in connection with automobile engines, the engine is frequently thrown out of operation in a remote neighborhood, necessitating the towing of the car. In double spark magnetos in which both sparks are produced from a single secondary winding upon the armature of the magneto, both ends of the secondary winding being disconnected from the primary winding, and separately connected with two spark plugs located in each cylinder of the engine through the proper distributing mechanism, it has been found practically impossible to wind a secondary coil upon the armature of the magneto under the limitations of size imposed in ordinary magneto construction with sufficient strength of insulation to stand up satisfactorily under long continued use, and short-circuiting of the secondary winding soon occurs, rendering the magneto inop-

erative. One of the objects of our invention is to obviate this difficulty by producing a two spark magneto having two primary coils and a secondary coil for each, separately connected, each to one of the spark plugs with which each cylinder is provided, and at the same time to provide for the operation of the magneto either as a two spark, or as a single spark magneto in case one of the coils should be rendered inoperative, the construction also providing for the operation of the ignition system from the battery through the magneto coils, or one of them, and the distributing mechanism of the magneto either as a two spark battery ignition system or a single spark battery ignition, so that the continuous operation of the ignition system and the consequent operation of the engine is insured. To this end therefore, the magneto, in addition to the usual primary and secondary coils carried by the armature, is provided with a second primary coil and a second secondary coil associated therewith, which are conveniently mounted upon a stationary portion of the magneto, the primary coils being connected in series and the secondary coils being connected through a double distributing mechanism with the double series of spark plugs with which the engine cylinders are provided, the usual condenser with which the magneto armature is ordinarily provided, in conjunction with the primary winding thereof, serving as the condenser for both primary coils. In connection with the magneto constructed as above indicated we prefer to provide a switch mechanism or switch mechanisms by means of which either of the primary coils may be short-circuited to convert the magneto into a single spark magneto and whereby one or both of the primary coils may be connected with the battery so as to operate as a two spark or one spark battery ignition system, when desired. This construction of magneto insures that under any and all ordinary conditions, the operator of an automobile engine equipped with such magneto will be assured of being able to operate the engine at all times, and will not be likely to be stranded with an inoperative engine at some remote point.

In the accompanying drawings, which show the preferred form in which we have

contemplated embodying our invention, in the construction of a magneto, and also one form of controlling switch for making the various electrical connections to enable the 5 magneto to be operated in the various ways hereinbefore indicated,

Figure 1 is a vertical sectional view of a magneto embodying our invention, and capable of being used either as a single or double 10 spark magneto, or in connection with the battery in either a single or a double spark ignition system.

Fig. 2 is a front view of the magneto with the housing for the periodic interrupter 15 removed.

Fig. 3 is a schematic diagram illustrating the relation of the parts of the magneto.

Fig. 4 is a wiring diagram illustrating the magneto and connections from the distributing 20 mechanism to the spark plugs of a double spark ignition system, and showing in connection therewith a battery and one form of switch which we find it convenient to employ in connecting the magneto for use as 25 a double spark magneto, as a single spark magneto, or with the battery for double spark or single spark ignition, the switch being shown in the "off" position.

Figs. 5, 6, 7, 8, 9 and 10 are detail views 30 showing the switch in different positions, the battery and line wire connections being indicated in exactly the same manner as they appear in Fig. 4, the other parts of the diagram being omitted to avoid unnecessary 35 duplication.

In the preferred embodiment of our invention herein illustrated, 1 represents the frame of the magneto in which is mounted the rotary armature 2 comprising the primary winding, indicated at 3, and the secondary winding, indicated at 4. The primary winding is connected in the usual manner with a circuit breaker or periodic interrupter, indicated at 5, the preferred form 40 of which is shown in Fig. 2, and comprises a rotary part carried by the armature and provided with a fixed contact, 6, and a movable contact, 7, carried by an L-shaped lever, 8, having a fiber heel 9, for engaging 45 suitable cams 10-10, for separating the fixed and movable contacts 6 and 7 in a well known way. In the magneto herein shown, the armature is wound so as to produce two sparks in each revolution of the 50 same, and accordingly two of the cams 10 are provided for this purpose, said cams being mounted on a cam ring 11 which is rotatable on the frame of the magneto by means of a timing lever 12 for the purpose 55 of advancing or retarding the spark in the usual manner. 13 represents the usual condenser, arranged in connection with the primary winding 3 and periodic interrupter 5 in the usual manner.

60 The magneto is provided with two dis-

tributors, each comprising a circular part, indicated at 14 and 15 respectively, having the usual distributing contacts 16, of which six are shown herein, the magneto, as shown, being arranged for firing a six cylinder internal combustion engine, and suitable means are provided for connecting each of these contacts of each distributing ring with a spark plug in one of the cylinders, there being two spark plugs in each cylinder indicated at 17 and 18 respectively, in the diagram Fig. 4. In conjunction with the distributing rings we preferably employ the usual distributing rotor, indicated at 19, and provided with two distributing brushes 20 and 21, respectively, insulated from each other, this rotor being located above the armature and driven therefrom by means of a pinion 22 on the armature shaft which engages a gear wheel 23 on the rotor, the 85 gears being arranged to drive the rotor 19 at a speed of one to three, or in other words, three revolutions of the armature to one of the rotor. One of the brushes, as the brush 20, is connected with a high tension terminal 90 rod 24, which is concentric with the rotor and is provided at its outer end with a spring actuated brush, 25, hereinafter referred to. The other distributor brush is connected to a metallic plate, 35, engaged by 95 a brush 34, which is connected by a wire or cable 33 with a stationary brush 32, engaging a slip ring 30 on the rotating armature of the magneto, the said slip ring being connected to one end of the secondary coil 4 100 of the magneto armature, the other end of which is connected to one end of the primary winding 3 in the usual manner. For the purpose of effecting two spark ignition, we employ an auxiliary primary coil and an 105 auxiliary secondary coil connected therewith, the said coils being stationarily mounted on the frame of the magneto, as clearly shown in Fig. 1, in which the magneto frame is shown as provided with a supporting plate 40 above the armature upon which is mounted the primary coil 41 and secondary coil 42, surrounding a soft iron core 43, the core and coils being contained in a suitable 110 case 44 of insulating material, and held in 115 position by a screw 45, extending through the center of the core and engaging a threaded opening in the stationary plate 40. A high tension terminal plate, 46, is provided at one side of the casing 44, in axial 120 alignment with the brush 25, and is connected with one end of the secondary coil 42, the other end being connected to the primary coil 41 as indicated as 47. The high tension terminal plate 46 and the plate 40 are 125 provided with separated contacts 48 and 49 constituting a safety spark gap for the high tension circuit. The primary coil is connected by means of a wire 50 with a low tension conductor plate 51 secured to but 130

insulated from the supporting plate 40, the said plate 51 being provided preferably with two brushes 52, 53, which bear upon a collecting ring 54 carried by the rotating armature 2 and to which the primary coil 3 of the armature is connected. We prefer to employ two of these brushes 52 and 53 so that in case of any accident to one of the same, the proper collection of current from the conductor ring 54 will continue through the other brush. The end of the auxiliary primary coil 41 opposite that connected by the lead wire 50 to the brushes 52—53, is connected by a wire 55 with a suitable binding post, 56, and the other end of the primary winding is connected by a wire 57 leading from the low tension contact plate 51 to a second binding, post, 58. The binding posts 56 and 58 extend through the casting of the magneto. From the contact 56 a main wire 60 is led and from the auxiliary contact 58 a second line wire, indicated at 61, is led.

Referring now to the schematic diagram illustrated in Fig. 3, it will be apparent that in the ordinary operation of the magneto, if the wire 60 is connected to ground, current will be generated in the primary coil 3 and conveyed through the primary coil 41 by means of the slip ring 54 and brushes 52—53 and connecting wire 50. When the primary current is broken by the separation of the periodic interrupter, the high tension current will be induced in the secondary winding 4 of the armature and the secondary winding 42 of the stationary coils, and these high tension or secondary currents will be separately transmitted to the brushes 20 and 21 of the rotor and simultaneously distributed to the appropriate spark plugs 17 and 18 for the cylinder which is at that moment in firing position. The magneto will therefore act under these circumstances continuously as a double spark magneto.

The apparatus can also be operated as a one spark magneto, by cutting out the auxiliary primary coil from the main circuit. This can be done by disconnecting the wire 60 from the ground connection and making the same connection with the auxiliary wire 61, it being connected to the other end of the auxiliary primary coil 41 eliminates said coil and its secondary coil from the circuit, and the magneto will now operate as a one spark magneto, the high tension current from the secondary armature coil 4 being distributed by the rotor brush 21 to one spark plug in each cylinder.

If the secondary coil 4 should become inoperative by reason of defective insulation, or otherwise, while the magneto is operating as a two spark magneto, the current generated in the main primary armature coil 3 would nevertheless pass through the auxiliary primary coil 41 and be interrupted by

the periodic interrupter, as previously described, the high tension current from the auxiliary secondary coil 42 being distributed by the rotor brush 20 to one of the spark plugs in each cylinder, so that the magneto 70 will operate to supply the ignition coils for the engine even though the armature secondary coil becomes defective.

It will also be understood that by connecting a battery in series with the primary 75 coils, as by connecting the wire 60 to the positive pole of the battery and operating the armature in the usual manner, the main and auxiliary primary coils may be energized from the battery to produce two 80 sparks in each cylinder from the main and auxiliary secondary coils. If the battery is connected to the wire 60, and assuming for example, that the secondary winding 4 of the armature has become defective, the battery current can be sent through the auxiliary primary coil 41 and the main primary coil 3, to the interrupter 5 and the high tension current generated in the auxiliary secondary coil 42 will be distributed 90 by the rotor brush 20 to one of the spark plugs in each cylinder. A battery may also be connected to the wire 61 so as to pass the battery current through the main primary winding 3 of the armature, to the periodic 95 interrupter 5, without passing it through the auxiliary primary coil 41, in which case the apparatus will act as a one spark ignition apparatus, the high tension current from the main secondary winding 4 being distributed by the rotor brush 21 to one spark 100 plug in each cylinder.

This construction, as will be readily understood, therefore, provides a wide range of operative effect and by making the necessary circuit connections, the device can be operated as a one or two spark magneto, as desired, or as a one or two spark battery ignition apparatus, as desired, and upon the failure of one or other of the secondary 110 coils, the magneto current or the battery current can be employed to energize the other secondary winding and produce a spark at one spark plug in each cylinder, all these effects being produced without any 115 change in the magneto itself by simply varying the electrical connections exterior to the magneto and insuring the continuous operation of the engine.

Referring to Fig. 4 we have shown one 120 form of switch mechanism which may be conveniently combined with the magneto for the purpose of making the connections before described, or any of them, but it will be understood that we do not limit ourselves 125 to this specific form of switch, as these connections may be made by means of other forms of switch or switches, if desired, and this particular switch apparatus is illustrated more particularly in order to more 130

clearly set forth the operation and advantages of our improved magnetos. As illustrated in Fig. 4, the switch comprises a circular series of contacts and a rotatable or oscillating switch member coöperating therewith. In the form herein shown, the switch comprises stationary contacts 70, 71, 72, 73, 74, 75 and 76, arranged in a circle. The contact 70 is connected with the wire 61 and a branch wire 61^a connects the wire 61 with the contact 72. The contact 71 is connected by wire 71^a with the ungrounded contact of the periodic interrupter in circuit with the primary coil 3 of the armature. 10 The contact 73 is connected to ground in any desired manner. The contacts 74 and 76 are both connected to the main wire 60, and the contact 75 is connected to the battery which is in turn connected with ground. It is to 15 be understood generally that the ground connections herein referred to are for purposes of completing the return circuit and are customarily made through the framework of the engine or magneto, but obviously may be made by return wire or wires if desired. 20 80 represents a rotatable or oscillating switch member pivotally mounted concentrically with the circular series of switch contacts just described. The switch 25 member 80 carries at one end a segment 81 in electrical contact therewith, and a segment 82 insulated therefrom, as by insulating material 83. The opposite end of the switch member 80 carries a short segment 84 30 in electrical contact with the switch member 80 and segment 81.

In Figs. 5 to 10 inclusive we have shown different positions of the switch which may now be briefly described. In Fig. 5 the 35 switch member is shown in the "off" position, the segment 81 being in engagement with the contact 70 but the segment 84 being located between contacts 73 and 74 so that no circuit is completed through the 40 magnet and the ignition system is inoperative when the switch is in this position.

In Fig. 6 the switch member 80 is shown in position to make contact through the segments 81 and 84 and the switch member 80 45 with the contacts 70 and 73, thereby connecting the wire 61 with the ground and short circuiting the auxiliary primary coil 40, as will be readily seen by reference to Fig. 4. In this position of the switch the magneto 50 will operate as a one spark magneto and high tension current will be distributed from the main secondary winding 4 to one spark plug in each cylinder.

Fig. 7 shows the switch rotated to its 55 third position, in which the segment 81 is brought into engagement with the contact 76 while the segment 84 is still in engagement with the contact 73. This connects the wire 60 with ground and establishes the main

circuit through the primary coils 3 and 41. 60 In this position of the switch the magneto will operate as a two spark magneto and high tension current from both of the secondary coils 4 and 42 will be distributed to produce two sparks in each cylinder simultaneously. 70 Fig. 8 shows a fourth position of the switch, in which the segment 81 has been moved into engagement with the battery contact 75 while it is still in engagement with the contact 76, leading to the wire 60. In 75 this position of the switch the battery current flows to the contact 75, thence over the switch segment 81 to the contact 76, thence over wire 60 to the auxiliary primary coil 41. It will be noticed that the segment 82 80 has connected the contacts 70 and 71, thereby short-circuiting the primary coil of the armature, so that the current passes from the auxiliary primary coil 41 by way of wire 61 to contact 70, thence by wire 71^a to the circuit breaker or periodic interrupter 5, and thence to ground. This arrangement enables the device to operate as a one spark battery ignition system, even though the armature coil or coils are inoperative by reason of being 85 burned out or grounded.

Fig. 9 shows a fifth position of the switch, in which the segment 81 is in engagement with the battery contact 75 and the segment 84 is in engagement with the contact 72. In 90 this position of the switch the battery current flows to the contact 75, thence across the switch member 80 to contact 72, thence by wire 61^a to the wire 61, thence by wire 50, brushes 52 and 53 and collecting ring 54 to 95 the primary coil 3 of the armature, and thence to the periodic interrupter 5, and ground. This arrangement enables the apparatus to function as a one spark ignition system, the auxiliary primary coil 41 being 100 out of the circuit, and the high tension current being distributed from the main secondary coil 4 and rotor brush 21 so that the device can be operated in this manner without utilizing either of the auxiliary coils. 105

Fig. 10 represents a sixth position of the switch in which the switch member 80 has been moved so as to bring the segment 81 into engagement with the battery contact 75 and the contact 74, which are thereby connected with the wire 60. The battery current will now flow from the battery to contact 75 across the segment 81 to contact 74, thence by wire 60 to the auxiliary primary coil 41, thence by wire 50, contact brushes 52-53 110 and collecting ring 54 to the main primary coil 3, and thence to the periodic interrupter 5, and ground, thus energizing both primary coils from the battery current and effecting the distribution of the high tension currents 115 from the secondary coils 4 and 42, independently to the rotor brushes 20 and 21, and producing two sparks in each cylinder simul-

taneously. In this position of the switch, the apparatus operates as a two spark battery ignition system.

The great and varied advantages of this invention will be readily apparent. In addition to enabling the operator to connect the apparatus in any of the various ways previously described for insuring the operation of the engine, it is also to be noted that the auxiliary coils 41 and 42 may be removed from the magneto for repair or re-winding, and the apparatus may still be operated as a one spark magneto ignition or a battery one spark ignition system, as desired, according to the position of the switch.

What we claim and desire to secure by Letters Patent is;—

1. The combination with an internal combustion engine, provided with two spark plugs in each cylinder thereof, a magneto having a main primary winding, a main secondary winding electrically connected thereto, a periodic interrupter in circuit with said main primary winding, and a distributor connected to the main secondary winding and to one of the plugs in each cylinder, of a stationary magnet comprising a core, an auxiliary primary winding connected in series with the main primary winding, and an auxiliary secondary winding connected with the auxiliary primary winding, and a second distributor connected with the auxiliary secondary winding and with the other spark plugs in said cylinders, said distributors each comprising stationary contacts, and a rotary contact, said rotary contacts being insulated from each other and rotating in unison to simultaneously and independently close the circuit from said secondary windings to both spark plugs in one cylinder at each period of ignition.

2. The combination with an internal combustion engine, provided with two spark plugs in each cylinder thereof, a magneto having a main primary winding, a main secondary winding electrically connected thereto, a periodic interrupter in circuit with said main primary winding, and a distributor connected to the main secondary winding and to one of the plugs in each cylinder, of a stationary magnet comprising a core, an auxiliary primary winding connected in series with the main primary winding, and an auxiliary secondary winding connected with the auxiliary primary winding, and a second distributor connected with the auxiliary secondary winding and with the other spark plugs in said cylinders, said distributors each comprising stationary contacts, and a rotary contact, said rotary contacts being insulated from each other and rotating in unison to simultaneously and independently close the circuit from said secondary windings to both spark plugs in one cylinder at each period of ignition.

nition, and means for rendering the auxiliary primary coil inoperative, to enable the apparatus to operate as a one spark magneto ignition apparatus.

3. The combination with an internal combustion engine, provided with two spark plugs in each cylinder thereof, a magneto having a main primary winding, a main secondary winding electrically connected thereto, a periodic interrupter in circuit with said main primary winding, and a distributor connected to the main secondary winding and to one of the plugs in each cylinder, of a stationary magnet comprising a core, an auxiliary primary winding connected in series with the main primary winding, and an auxiliary secondary winding connected with the auxiliary primary winding, and a second distributor connected with the auxiliary secondary winding and with the other spark plugs in said cylinders, said distributors each comprising stationary contacts, and a rotary contact, said rotary contacts being insulated from each other and rotating in unison to simultaneously and independently close the circuit from said secondary windings to both spark plugs in one cylinder at each period of ignition, a battery, means for placing the battery in circuit with the auxiliary primary winding, and means for placing the auxiliary primary winding in circuit with the periodic interrupter independently of the main primary winding, and for rendering the main primary winding inoperative to enable the apparatus to operate as a one spark battery ignition apparatus.

4. The combination with an internal combustion engine, provided with two spark plugs in each cylinder thereof, a magneto having a main primary winding, a main secondary winding electrically connected thereto, a periodic interrupter in circuit with said main primary winding, and a distributor connected to the main secondary winding and to one of the plugs in each cylinder, of a stationary magnet comprising a core, an auxiliary primary winding connected in series with the main primary winding, and an auxiliary secondary winding connected with the auxiliary primary winding, and a second distributor connected with the auxiliary secondary winding and with the other spark plugs in said cylinders, said distributors each comprising stationary contacts, and a rotary contact, said rotary contacts being insulated from each other and rotating in unison to simultaneously and independently close the circuit from said secondary windings to both spark plugs in one cylinder at each period of ignition, a battery, means for placing the battery in circuit with the auxiliary primary winding, and means for placing the auxiliary primary winding in circuit with the periodic interrupter independently of the main primary winding, and for ren-

dering the main primary winding inoperative, and means for independently rendering the auxiliary primary winding inoperative, whereby the device may be operated as a two 5 spark magneto ignition system, a one spark battery ignition system, or a one spark magneto ignition system.

5. The combination with an internal combustion engine, provided with two spark 10 plugs in each cylinder thereof, a magneto having a main primary winding, a main secondary winding electrically connected thereto, a periodic interrupter in circuit with said main primary winding, and a distributor 15 connected to the main secondary winding and to one of the plugs in each cylinder, of a stationary magnet comprising a core, an auxiliary primary winding connected in series with the main primary winding, and an auxiliary secondary winding connected with 20 the auxiliary primary winding, and a second distributor connected with the auxiliary secondary winding and with the other spark 25 plugs in said cylinders, said distributors each comprising stationary contacts, and a rotary contact, said rotary contacts being insulated from each other and rotating in unison to simultaneously and independently close the circuits from said secondary windings to both spark plugs in one cylinder at 30 each period of ignition, a battery, and means for connecting the battery in circuit with the primary coils and periodic interrupter.

6. The combination with an internal combustion engine, provided with two spark 35 plugs in each cylinder thereof, a magneto having a main primary winding, a main secondary winding electrically connected thereto, a periodic interrupter in circuit with 40 said main primary winding, and a distributor connected to the main secondary winding and to one of the plugs in each cylinder, of a stationary magnet comprising a core, an auxiliary primary winding connected in series 45 with the main primary winding, and an auxiliary secondary winding connected with the auxiliary primary winding, and a second distributor connected with the auxiliary secondary winding and with the other spark 50 plugs in said cylinders, said distributors each comprising stationary contacts, and a rotary contact, said rotary contacts being insulated from each other and rotating in unison to simultaneously and independently close the 55 circuits from said secondary windings to both spark plugs in one cylinder at each period of ignition, a battery, means for connecting said battery in the main circuit with said primary coils, and means for placing 60 the auxiliary primary coil in circuit with the periodic interrupter, independently of the main primary winding, and for rendering the main primary winding inoperative, whereby the device may be operated as a 65 two spark magneto ignition system, a two

spark battery ignition system, or as a one spark battery or magneto ignition system.

7. The combination with an internal combustion engine, provided with two spark plugs in each cylinder thereof, a magneto 70 having a main primary winding, a main secondary winding electrically connected thereto, a periodic interrupter in circuit with said main primary winding, and a distributor connected to the main secondary winding 75 and to one of the plugs in each cylinder, of a stationary magnet comprising a core, an auxiliary primary winding connected in series with the main primary winding, and an auxiliary secondary winding connected with 80 the auxiliary primary winding, and a second distributor connected with the auxiliary secondary winding and with the other spark 85 plugs in said cylinders, said distributors each comprising stationary contacts, and a rotary contact, said rotary contacts being insulated from each other and rotating in unison to simultaneously and independently close the circuits from said secondary windings to both spark plugs in one cylinder at 90 each period of ignition, a battery, means for connecting said battery in the main circuit with said primary coils, and means for rendering the main primary coil inoperative, whereby the device may be operated as a 95 two spark magneto ignition system, a two spark battery ignition system, or a one spark battery ignition system.

8. The combination with an internal combustion engine, provided with two spark 100 plugs in each cylinder thereof, a magneto having a main primary winding, a main secondary winding electrically connected thereto, a periodic interrupter in circuit with said main primary winding, and a distributor 105 connected to the main secondary winding and to one of the plugs in each cylinder, of a stationary magnet comprising a core, an auxiliary primary winding connected in series with the main primary winding, and an auxiliary secondary winding connected with 110 the auxiliary primary winding, and a second distributor connected with the auxiliary secondary winding and with the other spark 115 plugs in said cylinders, said distributors each comprising stationary contacts, and a rotary contact, said rotary contacts being insulated from each other and rotating in unison to simultaneously and independently close the circuits from said secondary windings to 120 both spark plugs in one cylinder at each period of ignition, a battery, means for connecting said battery in the main circuit with said primary coils, and means for independently rendering inoperative the main 125 primary coil and the auxiliary primary coil.

9. The combination in a magneto, of a rotary armature, provided with a main primary winding and a main secondary wind- 130

- ing, connected at one end to the primary winding, a periodic interrupter provided with a rotary part operated in timed relation with the armature shaft, and provided with separable contacts, one of which is grounded and the other of which is connected to one end of the main primary winding, a slip ring on the armature connected to the other end of the main primary winding, 70 a stationary magnet mounted on the frame of the magneto, and comprising a core, an auxiliary primary winding, and an auxiliary secondary winding having one end connected with the auxiliary primary winding, 75 a brush connected with one end of said auxiliary primary winding, and engaging said slip ring to connect the primary coils in series, and distributing mechanism comprising two independent circular series of 80 contacts and a rotor provided with two contacts, insulated from each other, and each connected to one of said secondary windings, and an electrical connection to said brush independent of said auxiliary primary winding for short-circuiting the latter.
10. The combination in a magneto, of a 85 rotary armature, provided with a main primary winding and a main secondary winding, connected at one end to the primary winding, a periodic interrupter provided with a rotary part operated in timed relation with the armature shaft, and provided with separable contacts, one of which is 90 grounded and the other of which is connected to one end of the main primary winding, a slip ring on the armature connected to the other end of the main primary winding, 95 a stationary magnet mounted on the frame of the magneto, and comprising a core, an auxiliary primary winding, and an auxiliary secondary winding, a brush connected with one end of said auxiliary primary winding, and engaging said slip ring to connect the primary coils in series, and distributing mechanism comprising two 100 independent circular series of contacts and a rotor provided with two contacts, insulated from each other, and each connected to one of said secondary windings, and an electrical connection extending to the ungrounded contact of the periodic interrupter for short-circuiting the main primary coil.
11. The combination in a magneto, of a 105 rotary armature, provided with a main primary winding and a main secondary winding, connected at one end to the primary winding, a periodic interrupter provided with a rotary part operated in timed relation with the armature shaft, and provided with separable contacts, one of which is 110 grounded and the other of which is connected to one end of the main primary winding, a slip ring on the armature connected to the other end of the main primary winding, 115 a stationary magnet mounted on the frame of the magneto, and comprising a core, an auxiliary primary winding, and an auxiliary secondary winding, having one 120 contact, a high tension connection from said brush to one of said rotor contacts, a high tension connection connected to the other rotor contact and extending axially of the rotor, a brush connected with said axial high tension connection, and a contact plate 125 on the magnet connected to the auxiliary secondary coil and engaging said last mentioned brush.
12. The combination in a magneto, of a 130 rotary armature, provided with a main primary winding and a main secondary winding, connected at one end to the primary winding, a periodic interrupter provided with a rotary part operated in timed relation with the armature shaft, and provided

end connected with the auxiliary primary winding, a brush connected with one end of said auxiliary primary winding, and engaging said slip ring to connect the primary coils in series, and distributing mechanism comprising two independent circular series of contacts and a rotor provided with two contacts, insulated from each other, and each connected to one of said secondary windings, an electrical connection to said 10 brush, independent of said auxiliary primary winding and an independent electrical connection extending to the ungrounded contact of the periodic interrupter.

In testimony whereof we affix our signatures.

VICTOR W. KLIESRATH.
FREDERICK A. HOYT.
